UNITED STATES PATENT OFFICE.

DEMETRIUS D. LITTLEJOHN, OF STATESVILLE, NORTH CAROLINA.

PLOW-BLADE.

1,115,219.

Specification of Letters Patent. Patented Oct. 27, 1914.

Original application filed November 24, 1913, Serial No. 802,775. Divided and this application filed March 17, 1914. Serial No. 825,300.

To all whom it may concern:

Be it known that I, DEMETRIUS D. LITTLEJOHN, a citizen of the United States, residing at Statesville, in the county of Iredell 5 and State of North Carolina, have invented new and useful Improvements in Plow-Blades, of which the following is a specification.

This invention relates to plow blades, and 10 it comprehends the provision of an improved device of the character stated which is designed, primarily, for use in connection with, or as a part of, a subsoil attachment, and which is so constructed that the point 15 or blade proper may be applied to or removed from its carrier without ordinarily entailing rearrangement of other parts, and, when in place on the carrier, will have its tip or terminal disposed exactly in the line 20 of draft.

An embodiment of the invention is illustrated in the accompanying drawing, whereof:—

Figure 1 is a side elevation of a subsoil 25 attachment equipped with the improved blade and applied to a plow, the latter appearing in dotted lines; Fig. 2 is a perspective view of the attachment; and Fig. 3 is a detail vertical section taken on line 30 3—3, Fig. 2.

The subsoil attachment, as represented, consists of two main parts or elements, namely: the ground-treating implement or blade 1 and its support 2. The latter element is preferably, though not necessarily, of the type shown and described in my prior application, Serial Number 802,775, filed November 24, 1913, of which the present case is a division, and since reference may be 40 had to said application for a complete understanding of this element, extended explanation is omitted herefrom, it being considered sufficient for present purposes to state that it consists of front and rear bar-like members 2' and 2² arranged one behind the other and having their mutually-adjacent ends overlapped and adjustably connected together, to permit swinging movement of the rear member in a vertical plane. The front 45 portion 2³ of this compound bar is attached in some suitable manner to the plow beam 3, and, whereof the type just specified, conforms, substantially, to the shape of the downwardly-curved rear portion or neck of 50 said beam directly against which it is ar-

ranged. The rear portion 2⁴ of the bar is curved, as shown, for a purpose subsequently explained.

The ground-treating implement 1 preferably consists of a point or blade proper 1', and a carrier therefor composed of a base plate 1² and a face plate 1³, the latter being arranged against the front of the said base plate and fastened thereto by bolts 1⁴. The plates 1² and 1³ are formed with vertical 60 centrally-located slots 1⁵ and 1⁶, and the first-named plate is also provided with a rearwardly-projecting web 1⁷ that extends from end to end thereof and is arranged at one side of slot 1⁵. The two slots 1⁵ and 1⁶ 65 register and are of the same size, and that face of web 1⁷ which is adjacent said slots is flush with the corresponding walls thereof. The rear terminal portion 2⁴ of the supporting bar 2 projects through said slots 70 and is fastened to said web by bolts or other suitable devices 1⁸, the web being formed with a series of bolt holes to permit an adjustment of the ground-treating implement as a whole with respect to said bar, as will 75 be understood from the drawing. The length of the face plate 1³ is less than that of the base plate 1², and since the top edges of these two plates are arranged flush with each other, a space is left at the lower portion of the said plate 1² against which is arranged the upper portion 1¹¹ of the point 1', the combined length of this portion and of the plate 1³ being equal to that of the plate 1². The aforesaid upper portion of the 80 point is secured by bolts 1⁹ or other fasteners to the plate 1², and these fasteners are preferably removable, thereby permitting the point to be detached and sharpened and, if necessary, replaced by a new point. 85

It will be observed from the foregoing that the slots in the carrier part of the ground-treating implement are arranged exactly central thereof, and that the tip or terminal of the point is in line with these 90 slots, and, hence, is exactly in the line of draft. Also, the point is itself readily detachable from the carrier, but, under ordinary circumstances, does not entail the removal of any other parts when sharpening 100 105 or the point or substitution of one point for another is contemplated.

Having fully described my invention, I claim:—

1. The combination, with a support; of 110

a blade carrier embodying a plate formed with a vertical slot through which the rear end of said support projects, and with a rearwardly-extending, vertical web located 5 at one side of said slot and against which said support end is directly fastened; and a blade connected to the lower portion of said carrier.

2. The combination, with a supporting 10 bar having a downwardly-curved rear end; of a blade carrier embodying a plate formed with a vertical slot through which the curved end of said bar projects, and with a rearwardly-extending, vertical web located 15 at one side of said slot, said bar end extending downwardly along and being secured directly against said web; and a blade connected to the lower portion of said carrier.

3. The combination, with a supporting 20 bar having a downwardly-curved rear end;

of a blade carrier embodying juxtaposed, connected, base and face plates formed with registering vertical slots through which the rear end of said bar projects, the base plate projecting below the face plate and having 25 a rearwardly-extending, vertical web formed upon its outer face at one side of the slot therein, against which web said bar end is directly fastened; and a point having its upper portion fastened to the projecting 30 lower portion of said base plate, with its upper edge flush against the lower edge of said face plate.

In testimony whereof I have hereunto set my hand in presence of two subscribing wit- 35 nesses.

DEMETRIUS D. LITTLEJOHN.
